DYE SPATTERING MACHINE

Harry C. Wolfenden, Attleboro, Mass.

Application December 22, 1937, Serial No. 181,176

1 Claim. (CL. 68—200)

My present invention is a novel and improved machine for use in dyeing articles by splashing or spattering dye thereon, and more particularly by using an uneven spotting or spattering action.

In the present methods of applying dye to yarn, cloth, or fabric various apparatus are employed to produce spotted effects, but all such prior machines and methods have resulted in substantially regular spots, lines, or figures. In my present invention I have devised a machine for producing irregular and non-recurring spots, lines, and mottled effects on yarn, cloth, or fabric by means of a spattering, splashing or throwing operation of the dye against the material being treated, thus resulting in irregular and non-recurring spots of dye or coloring material on the articles.

I effect this new result preferably by conveying the yarn, cloth, or fabric thru a machine, or machines, and subjecting the same to a splashing action of the color or colors which it is desired to apply to the material being treated. By a series of such splashing operations, feeding the material thru successive machines, I am enabled to produce irregular and mottled colored effects, thus producing my novel and improved article by the method and machine operations hereinafter explained.

In carrying out my present invention I provide means to treat the articles, such as yarn for example, by drawing the same preferably thru a moistening treatment; then thru a spattering apparatus, then thru a drying treatment, and thence to a reeling machine where the yarn is wound into skeins.

Where successive colors are to be splashed or spattered on the yarn, I may conduct the same thru successive apparatus for the splashing and drying and then onto the winding or reeling machine. Strips of fabric, cloth, or other articles may be similarly fed thru these successive machines or thru a single machine when only one color is being applied.

My novel apparatus consist of means to feed dye or color from a trough or tank by a series of rotating teeth or blades capable of yielding and springing, and having the ends strike against a projection, or projections, such for example as a roller in the line of travel, whereupon the blades as they leave the projection will throw, splash, or spatter spots of dye upon and against the material which is being fed therethru.

Preferably I provide moistening means which will still further enable the splashing dye to

permeate the material and, preferably also I conduct the now splashed material over or thru a drying device to set the spots thus splashed. Thereupon, a successive dyeing operation of a different color can be applied in the line of travel of the material, so that varying mottled effects are produced quickly, economically, and successively as the material is fed thru the apparatus and on to a winding reel.

Additional features consist in means to control the area and effective extent of the spattering action, means to collect and return the surplus coloring material thrown or spattered; means to vary the speed of travel or the level of the coloring material and, hence, to control the amount of same being thrown by the spattering devices, means to effect the moistening, and means to protect ready accessibility in the cleaning of the apparatus.

Further features, advantages, novel combinations, and details will be hereinafter more fully pointed out and claimed.

Referring to the drawings illustrating a preferred embodiment of the invention.

Fig. 1 is a side view partly in cross-section illustrating the moistening, splashing, and drying of the material as it is fed therethru;

Fig. 2 is an enlarged diagrammatic form illustrating a splashed fragment of yarn which has been subjected to my method and apparatus;

Fig. 3 is a cross-sectional plan view on the line 3—3 of Fig. 1;

Fig. 4 is a fragmentary view of the side of the apparatus looking from the drive end of Fig. 3;

Fig. 5 is a vertical cross-sectional view on the line 5—5 of Fig. 1;

Fig. 6 is a cross-sectional view on the line 6—6 of Fig. 1;

Fig. 7 is a cross-sectional view on the line 7—7 of Fig. 1;

Fig. 8 is a diagrammatic view showing the feeding of yarn from a plurality of spools thru my apparatus on to a skein-winding reel;

Fig. 9 is a diagrammatic view illustrating a plurality or series of treatments and apparatus therefor;

Fig. 10 is a fragmentary view in perspective of the spattering teeth;

Fig. 11 illustrates a fragmentary set of teeth with rubber-retaining strips to prevent crystallization;

Fig. 12 is a fragmentary side view illustrating the manner of holding the teeth and rotor, and

Fig. 13 is a modification showing a doctor roll. In the attached drawings, I have illustrated

5 yarn 50 is threaded and thence over the moistening rolls 71, and thence thru the comb teeth 56 on the slide 55 and so thru the slot 48 and across the front of the apparatus, the line of feed being in the direction of the arrow, Fig. 1, over a dryer and thence to the winding reel, where each thread is wound into a skein.

10 In order to insure a uniform contact of the yarn 50 over the surface of the moistening rolls 71 I prefer to apply a guide roll 85 mounted closely adjacent the teeth 56. This guide roll 85 is preferably hinged at 86 to a stud 87 mounted on the cover 30 and with the other end detachably secured to the corresponding stud 88 resting 15 in a slot in said stud so that the free end of the guide roll 85 may be raised on its hinge 86 when threading the yarn 50 thru the comb teeth 56. Thereupon the rod 85 is swung downwardly into position bearing against the yarn 50 and insuring contact of the same over the moistening roll 71, as best shown in Fig. 1.

20 The spattering devices within the tank 3 and cover 30 will now be described. These consist in a series of individual spring teeth 90 arranged 25 in rows and secured to the hub 12 mounted on the shaft 10. These teeth 90 may be formed in any desired manner but preferably, and as herein shown, I stamp or cut the same from a metal plate 91, which plate is solid at the lower portion where it is adapted to fit within slots or 30 grooves 92 in the rim portion of the hub 12, and preferably also I attach to the hub as additional supporting means spacers and holders for the teeth 90, a series of U-shaped metal flanged 35 members 95 having the bottom or U portion secured to the hub 12 by screws 96, see Fig. 12. These U-shaped flanges 95 act to hold and support the teeth 90 while permitting the diameter of the hub 12 to be of relatively slight diameter.

40 I may also secure to the teeth 90 or to the supporting plate 91 strips of rubber on each side 98, 99, see Fig. 11, which will fit or slide between the flanges of adjacent U-shaped members 95 in alignment with the slots 92 in the hub and 45 prevent crystallizing of the teeth during the springing of said teeth to effect the throwing, spattering, and spotting action of the dye within the tank 3 on the yarn 50.

50 In order to have the teeth 90 uniformly positioned in the respective rows, I prefer to thread each end of the hub 12 and fit thru a clamping nut 100, which nut is held in position by the threading of the locking nut 101 thereagainst, a washer 102 being fitted between the clamping 55 nut 100 and the locking nut 101. One or more set screws 105 are provided to clamp the hub 12 to the shaft 10, see Fig. 5.

55 In order to drain the tank 3, I provide a plug 110 threaded into a tapped recess 109 in the bottom of the tank 3 to draw off the dye contained therein and for flushing and cleaning the same after the machine has been in service.

60 As previously explained the height of the dye-containing bottle 25 in the conduit 21 will regulate the level within the tank 3 into which the teeth 90 dip during the rotation of the shaft 10. Raising the height of the bottle 25 by washers (not shown) between the same and the flanged holding portion 22 will increase the height of the 65 dye or coloring liquid in the tank 3 and increase the amount thrown or spattered by the teeth 90.

70 While rotation of the shaft 10 will effect a throwing of the dye against the yarn 50 thru the opening between the sliding plates 35 and 75 36, yet I prefer to effect a more positive and

75 forceful dye-throwing action, and for this purpose I provide an adjustable member 112 in position so that the entire teeth 90 of the series will contact with the same and spring by as the shaft 10 continues its rotation. This gives a more positive and forceful throwing action of the dye against the yarn 50 and aids in the penetration of the yarn by the coloring material thus thrown.

80 I also find it desirable to adjust the position of this contact member 112 and, therefore, I mount the same on a slide 115 secured by a set screw 116 thru a slot in the slide 115 to the extension 118 on the edge of the tank 3.

85 At the left, viewed in Fig. 1, a thumb nut 120 is secured to the slide 115 and rotates thru an upstanding lug 121 also secured to the extension 118. The thumb nut 120 is secured to a shaft 125, which shaft has its end threaded and in engagement with the correspondingly 90 threaded recess in the slide 115, so that manipulation of the thumb nut 120 will move the slide 115 and consequently the contact member 112 toward and from the teeth 90 to regulate the 95 springing effect and, hence, the throwing and splashing action, as will be readily understood.

100 After the yarn is treated by the operator or throwing of the teeth 90 springing by the contact member 112, I prefer to effect an immediate drying of the treated yarn, and for this purpose I provide a drying device effective to dry the treated yarn as soon as it comes out of the apparatus. Any suitable drying element can be employed, but as herein shown, I provide a rotating fan 124 mounted on a shaft 121 and rotated by an electric motor 122 enclosing the fan in a box 130 mounted on the bench 1 adjacent the spattering apparatus. If desired, a heater 131 can be fitted within the box 130 so that the warm air will be driven by the fan 124 upwardly thru the open top of the box 130 as the 105 yarn 50 passes thereover.

110 A plurality of series of these dye-throwing devices can be arranged to treat the yarn 50 successively in its line of travel from a rack or 115 reel 135, see Fig. 8, to the winding device 136 on which the skeins are wound and then the winding device 136 collapsed, and then the skeins removed.

120 As shown in Fig. 9, I have shown a series of 125 three dyeing apparatus, each with or without the guiding devices; and in such a series I find that one moistening device and one drying device is sufficient. To rotate the spattering and moistening devices, any suitable source of power 130 can be utilized, transmitting the same thru the sprocket chain 140 to the wheel 18 secured to the shaft 10 and from the pulley 17 also secured to the shaft 10 and to the pulley 15 by a belt 141.

130 Various colors can be thus applied to the yarn 135 50 during its continual travel, and the spotting, splashing, and coloring is of a mottled and random-like design, entirely unregulated and irregular.

140 I have shown in Fig. 13 the provision of a doctor roll which will pick up the surplus dye, (when 145 yarn is being treated), which is thrown thru the strands of yarn and might strike against the bottom of the trough 53 and, hence, drip down upon the yarn before the same passes thru the apparatus and beyond the apron 40. Thus the yarn might be spotted in an undesirable way, particularly when the sliding guides 35 and 36 are open to their fullest extent. To prevent such dripping from the trough 53, I may provide a 150
